UNITED STATES PATENT OFFICE.

CHARLES P. R. THIEL, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

WARP COMPRESSOR.

Application filed January 26, 1923. Serial No. 614,995.

To all whom it may concern:

Be it known that I, CHARLES P. R. THIEL, a citizen of the United States, and a resident of North Andover, county of Essex, State of Massachusetts (whose post-office address is 55 Prescott Street, North Andover, Mass.), have invented an Improvement in Warp Compressors, of which the following description, in connection with the accompanying drawing, is a specification, like characters on the drawing representing like parts.

This invention relates to mechanism for compressing the warp during the beaming operation.

The object of the invention is to provide a warp compressor so constructed as to produce an equal uniform and opposite rolling pressure against the warp mass on the beam as it increases in diameter.

The object of the invention is further to eliminate the disadvantages arising from applying compression to the warp beam at one side only.

The object of the invention is further to insure during the compression the maintenance of a perfectly cylindrical and compact warp mass on the beam.

The object of the invention is further to enable any required degree of pressure to be applied to the warp beam by means of pressure applied at opposite sides in equal amounts and, therefore, producing no material strain on the warp beam or the guides thereof.

The object of the invention is further to provide a warp compressor having a pair of compression rolls rotarily mounted in supports movable toward and from the beam at opposite sides thereof with means connecting the supports and acting as the rolls are forced apart by the increasing diameter of the warp mass to cause the rolls to maintain an equal, uniform and opposite pressure against the warp mass.

The object of the invention is further to provide novel means for securing and adjusting the amount of the pressure applied by the compression rolls to the beam at opposite sides thereof.

The object of the invention is further to provide in a single unit a combined warp beam and compressor embodying the invention supported on a movable frame whereby

the entire unit may be moved from place to place as required.

The object of the invention is further to provide a warp beam compressor comprising a pair of compression rolls movable parallel to and toward and from the axis of the warp beam at opposite sides thereof and acting to maintain an equal uniform and opposite pressure of the rolls against the warp mass on the beam and so arranged that the rolls may be adjusted longitudinally to enable a warp mass of greater length than the rolls to be compressed.

These and other objects and features of the invention will appear more fully from the accompanying description and drawings and will be particularly set forth in the claims.

In the drawings;

Fig. 1 is a front elevation partially broken away to show certain details of construction and disclosing a preferred form of a combined warp beamer and compressor embodying a preferred form of the present invention;

Fig. 2 is a top plan view of the warp compressor shown in Fig. 1;

Fig. 3 is a view in vertical cross section taken on the line 3-3 of Fig. 2 and on a larger scale;

Fig. 4 is a view in vertical cross section of the let-off mechanism taken on the line 4-4 of Fig. 2;

Fig. 5 is a view in side elevation of ratchet mechanism forming a part of the device;

Fig. 6 is a view chiefly in longitudinal vertical cross section showing one of the adjustable drums forming a part of the device;

Fig. 7 is a front elevation of a warp compressor embodying the invention separate from the beamer and constructed to be moved into connecting position with a beamer.

It is frequently desirable that warp when it is wound upon a beam for use in a loom or other textile machine shall be compressed into a compact mass. When this is done it is necessary that the warp mass shall be uniformly compressed throughout during the winding operation of the warp upon the beam and it is necessary that the warp mass shall be perfectly cylindrical throughout. If the warp beam springs during the compressing operation owing to unbalanced

pressure then the warp mass departs from the cylindrical form, the warp is not compressed evenly and highly undesirable results are obtained in the subsequent handling of the warp.

In the present invention the compression is applied in opposite directions to opposite sides of the warp beam so that there can be no tendency to spring or distort the warp beam or its gudgeons and consequently the pressure is applied to the warp beam evenly and uniformly throughout. Furthermore the pressure by means of this invention may be adjusted to any desired amount so as to produce any desired compactness in the mass of warp as it is wound on the beam.

The drawings illustrate a simple practical and preferred form of mechanism for securing these essential results. The mechanism illustrated also contains many features of novelty in the more or less specific means by which the broad features of the invention are secured.

A warp beamer of a generally familiar type is illustrated. This device comprises a frame 1 in which is mounted a shaft 2 carrying a large internal gear 3 at one side of the frame. One end of the gudgeon of a warp beam 4 has a bearing in a socket at the end of the shaft 2 while studs 5 project from the face of the gear 3 into recesses in the adjacent head 6 of the beam. Thus rotation of the shaft 2 imparts rotation to the warp beam. The gear 3 is rotated by a train of gearing from a suitable source of power as a belt running over the fast and loose pulleys 7.

It is essential that the opposite end of the warp beam gudgeon shall be supported in alignment with the shaft 2 and that the warp compressing mechanism shall be supported in accurate defined relation to the warp beam. These mechanisms may be all mounted upon the floor in the required position but, as involving a further feature of the invention, the entire mechanism is illustrated in Fig. 1 as supported by a single movable rigid frame. This frame 8 which may be of any suitable construction has mounted thereon and depending there beneath journal brackets 9 in which are journalled the supporting rollers 10. These rollers in turn are shown for convenience running on tracks 11 thus enabling the entire beaming and compressing mechanism to be moved from place to place in the mill as may be required.

The frame 1 of the warp beamer is shown as bolted at 12 to the movable frame 8. At the opposite end the supporting stand 13 is mounted in fixed relation on the warp compressor and thereby is mounted on the movable frame 8. This supporting stand 13 presents an open bearing in which the end gudgeon 14 is journalled in accurate align-

ment with the shaft 2. A guide roll or bar 15 for the warp is mounted parallel to and above the warp beam, one end resting in a bracket 16 on the frame of the beamer and the other end in an open bearing 17 at the top of the outer supporting stand 13.

In the preferred form of the invention illustrated the required rolling pressure is imparted to the warp mass being wound on the warp beam at opposite sides thereof by a pair of freely rotatable compression rolls 18 and 19. Each of these rolls is rotarily mounted in a suitable support movable toward and from the axis of the warp beam so as to maintain each compression roll in parallelism with the said axis. Preferably each compression roll is mounted in a set comprising a plurality of similar supports and preferably also each of these supports secures its movement toward and from the warp beam by being pivotally mounted at its lower end beneath the warp beam so as to swing toward and from the warp beam.

An opposite pair of the supports for the compression rollers is shown in side elevation in Figure 3. The supports 20 carrying the compression roll 19 are secured at their lower ends to a shaft 21 extending parallel to the axis of the warp beam and having its bearings in suitable supporting brackets 22 extending transversely of the machine and, as illustrated, bolted at 23 to the main frame 8. In a similar manner the supports 24 carrying the compression roll 18 are mounted on a similar shaft 25. These shafts 21 and 25 at their outer ends are journalled in an outer transverse bracket 26 also, as illustrated, bolted at 27 to the main frame 8, the outer ends of these shafts serve as a convenient means for supporting the outer stand 13 and insuring its accuracy of position. The stand may, therefore, readily be adjusted longitudinally of the shafts to provide for different lengths of warp beams.

The number and the spacing of the supports 20 and 24 of the respective sets of supports will vary according to the particular requirements. Four such supports are illustrated in each set as being sufficient for the ordinary run of work.

Each compression roll is journalled in a recess 28 in each support and rests upon anti friction rolls 29 journalled on axles 30, 31 and 32. The axle 30 extends through and is common to the uppermost anti friction roll 29 of each set of supports so as to form a guard to prevent the operator or his clothing being caught and drawn in between the compression roll and the warp beam. Such a guard is particularly important at the front of the compressor where the contacting peripheries of the warp mass and the compression roll are moving downwardly.

While it is desirable that the compression

rolls 18 and 19 acting at opposite sides of the warp beam shall each be of substantially the length of the warp mass being wound upon the beam still the desired results can be secured and a substantial degree of adjustment permitted by this invention to compress beams of varying length. This adjustability is secured by providing for the relative longitudinal adjustment of the compression rolls in their supports. Thus by adjusting one compression roll in one direction and the other in the opposite direction the desired equality of opposite pressure may be secured on a beam, the warp mass of which has a greater length than that of the compression rolls.

In the illustration the warp beam is shown as provided with false heads 33 of a familiar type positioned on the warp beam at a greater distance apart than the length of the compression rollers 19 and 20. To take care of this condition the compression roll 19 is adjusted longitudinally, for example to the left, until its end comes against the false head 33 at the left while the opposite compression roll 20 is adjusted to the right until its end comes against the false head 33 at the right. Thus pressure is produced over the entire warp mass and with entirely satisfactory results. Suitable gauges are provided for positioning and holding the compression rolls in longitudinal adjusted position to prevent them from creeping away from the heads. As illustrated similar gauges each comprising a shank 34 and a head 35 are mounted in and longitudinally adjustable of each of the endmost supports of each set of supports. They are each locked in place by a suitable set screw operated by a handle 36. In the adjustment illustrated in Fig. 2 the gauge at the right hand end of the compression roll 19 will be positioned so as to extend over the right hand end of the roll and hold it between the head 35 of the gauge and the false head 33 of the beam at the opposite end. In a similar manner the gauge at the left hand end of the compression roll 20 will be positioned to hold that roll with its right hand end against the false head 33 at the right hand end of the beam. Thus any two or all of the gauges may be used according to the particular conditions.

Novel and efficient means are provided by this invention for maintaining the required equal uniform and opposite pressure of the compression rolls on the warp mass as it increases in diameter and forces the rolls apart. As the supports of each set carrying the compression rolls move simultaneously and to the same extent the required force is conveniently applied to a single element and distributed therefrom to the supports at one side and from these to the supports at the opposite side.

In the construction illustrated a shaft 37 extending parallel with the compression roll 19 and the shaft 21 is journaled in the supports 20 of the set at the front of the machine. Rotation of this shaft 37 is retarded by a friction let-off mechanism, the preferred form of which is shown in detail in Fig. 4. For this purpose a friction drum 38 is splined at 39 to the shaft 37. The periphery of this drum is clasped by a two part clamp. The parts 40 and 41 of this clamp are substantially semi-circular and are provided at their inner face with a friction facing 42 of leather or other suitable material. At one side of the drum these parts are hinged together as by the bolt 43 having a loose fit therein while at the opposite side the clamp parts project to form arms 44 and 45. The arm 44 at its lower end is conveniently journaled on the shaft 21. The required friction between the clamp and the drum is secured and adjusted in amount in a novel and efficient manner. A spring 46 preferably of a comparatively heavy leaf form abuts the outer face of the arm 44 and a bolt 47 is provided which extends transversely of and connects the arms 44 and 45. This bolt at its outer end is provided with a pair of lock nuts 48 engaging the outer face of the spring 46 through which the bolt also passes. At its inner end the bolt is connected to the arm 45 so as to be longitudinally adjustable thereof. As a simple means for securing this adjustment the inner end 49 of the bolt is journaled on a pin 50 which is eccentric to the stud 51 journaled in the lower end of the arm 45. A handle 52 projects from the shaft 51 to within reach of the operator. Consequently by moving the handle 52 up or down the position of the eccentric pin 50 is changed to release or apply the friction between the clamp and the drum and by adjusting the nuts 48 on the bolt the amount of the friction is controlled. A stop 53 in the form of a collar is secured to the bolt 47 on the opposite side of the arm 44 from the spring 46 and is so positioned that when the handle 52 is moved to release the friction on the drum this stop engages with the face of the arm 44 and neutralizes the action of the spring 46.

In order that the friction on the drum may not be entirely released but that a light friction may still be maintained between the clamp and the drum an auxiliary bolt 54 is provided extending through the arms 44 and 45. A relatively light spring 55 surrounds this bolt between the arm 45 and a hand nut 56 on the end of the bolt. Hence the spring 55 may be adjusted to give the required light holding friction when the main friction on the drum is released.

The shaft 37 carries adjacent each support 20 at one side thereof an anchor socket

57 and at the other side thereof a drum 58 for a flexible connector such as a wire cable. The anchor socket 57 is loose on the shaft while the drum 58 is splined at 5 59 thereto. The drum at one side is provided with a flange 60 and at the other side with a hub 61 over which fits a take-up collar 62. This collar is held in any 10 desired position of rotary adjustment with respect to the drum by a set screw 63 passing through the collar and abutting the hub 61.

15 The opposite support 24 of each pair has journalled thereon an idler roll 64 and beneath the warp beam a pair of guide rolls 65 and 66 are journalled on a shaft 67 mounted intermediate the shafts 21 and 25 in the supporting brackets 22.

20 The flexible connector employed must be of a substantially non-stretchable character and of great strength. For this purpose a suitably formed wire cable 68 is illustrated. One of these cables is provided for each pair of supports 20 and 24. The cable at 25 one end is firmly secured in the anchor socket 57. From thence it passes beneath the guide roll 65 up around the idler 64 on the opposite support down beneath the guide roll 66 and thence around the drum 30 58 to which the end is secured by means of the take-up collar 62. For this purpose the end is threaded through an aperture in the collar and firmly locked by the set screws 69. Protection against injury to the operator is had by suitable guards wherever 35 necessary and such a guard is shown at 70 surrounding the idler 64. This idler has its plane of rotation pointing in the general direction of the lower portion of the 40 periphery of the guide rolls 65 and 66 but, as the angle of this plane changes somewhat as the supports move apart, deflecting guide rolls 71 are journalled on the support 24 beneath the connector 68 and adjacent the 45 idler 64 thus preventing any binding of the idler 64. The flexible non-stretchable connector such as the wire cable 68 forms a very efficient means for securing equality in the pressure exerted by the compression rolls 50 at the opposite sides of the warp beam. The take-up collars form a simple and effective means of adjusting each connector so that the force exerted by the supports 55 of each pair may be the same. All that it is necessary to do is to loosen the set screw 63 and wind or unwind the collar 62 on the drum 58 until the connector in each case pulls the supports together with the same amount of force.

60 After the several flexible connectors have been tightened up to produce a uniform pressure, the amount of compression exerted by the compression rolls on the warp mass on the beam is determined by the friction 65 let-off already described and is under per-

fect control of the operator. By shifting the handle 52 the amount of this friction is varied being greatest when the handle is in the lowermost position and gradually diminished until the handle reaches the uppermost or releasing position. In addition by varying the number of leaves of the spring 46 and by adjusting the nuts 48 on the bolt 47 there is no practical limit to the amount of compression that may be applied, and as the force exerted by each compression roll is opposed by that exerted by the other through the medium of the connector there can be no injury done to the warp beam or its gudgeon, no springing of the warp beam, and the winding of a firmly compacted cylindrical mass of warp on the beam is assured.

65 The supports are separated to permit the removal of the beam after the beaming operation is completed and brought together again after the fresh beam is placed in position by a pawl and ratchet mechanism shown in detail in Fig. 5. A sleeve 72 is secured at a convenient point to the shaft 37. This sleeve carries rigid therewith two ratchet wheels 73, one having the teeth pointing in one direction and the other having the teeth pointing in the opposite direction. Between the ratchet wheels and 75 on the sleeve 72 is journalled a pawl carrier 74 having a socket in which may be inserted a handle 75. This pawl carrier carries pawls 76 co-operating with one ratchet wheel and 77 co-operating with the other. 100 A spring 78 extends from the pawl carrier 74 down to a collar 79 on the shaft 21 or to some convenient point at the bottom of the machine and serves to counterbalance the pawl carrier and maintain it normally 105 in upright position. It will thus be seen that by throwing the proper pawl into engagement with the proper ratchet wheel and 110 rocking the handle 75 the shaft 37 may be rotated in either direction. Consequently at the end of the beaming operation the handle 52 is thrown to releasing position leaving the light friction, resulting from the spring 55, on the let-off mechanism and the shaft 37 is then rotated to unwind the 115 drums 58 and allow the supports to move apart.

120 The latches 80 are pivoted at an intermediate point as for example on the shaft 67 between each pair of supports and are provided with hooks 81 adapted to catch on studs 82 on the supports and hold the supports in open position. If it is necessary to open the supports further to remove a warp beam wound with a very large 125 mass of warp or for any other purpose they may be allowed to swing way apart and even down to the floor. As these supports with the compression rolls are quite heavy 130 a counterbalance is provided therefor ex-

eriting its main effect after the supports swing so as to carry their center of gravity past the axes of the shaft 21 and 25 respectively. This counterbalancing mechanism is shown in the form of coiled compression springs 83. Each spring is provided with a loop-shaped member 84 which is secured at an intermediate point beneath the warp beam as by engaging over the shaft 67, passes through the spring 83 and hooks over the outer end thereof at 85. Each spring is also engaged at its inner end by a hooked rod 86 connected at its outer end to a chain 87 extending about the periphery of, and secured by a bolt 88 to, a collar 89 secured to the shaft carrying the support. These counter balancing springs can be located at any desired positions and they can readily be so proportioned and arranged that the heavy weight of the supports and compression roller is substantially counterbalanced and no excessive force is required to lift the supports back to operative position or to a position where they may be brought together by the pawl and ratchet mechanism.

When, therefore, the operator by means of the handle 52 releases the main friction on the drum, the two sets of supports carrying the compression rolls are readily moved away from the beam or toward the beam by operating the handle 75.

In Figure 7 a warp compressor embodying the invention is shown mounted independently of the beamer so as to constitute a single portable unit. In this form the entire mechanism is mounted on a rigid frame 90, the various supporting parts such as the brackets 22 and 26 being bolted to this frame. This main frame 90 in turn is illustrated, for convenience, as carried by a supporting frame 91 having the depending brackets 92 in which are journalled the supporting rollers 93. This warp compressing unit may, therefore, be pushed about upon the floor or upon tracks to bring it into alignment with a suitable beamer.

Having thus described the invention what is claimed as new and desired to be secured by Letters Patent, is:

1. A warp beam compressor comprising means for rotarily supporting the warp beam, a frame, a pair of supports mounted on the frame at opposite sides of and movable toward and from the axis of the warp beam, a compression roll rotarily mounted in each support in parallelism with the axis of the warp beam and engageable with the warp mass on the beam at opposite sides thereof, and means for maintaining an equal uniform and opposite resistance to the movement of the supports away from the beam as the diameter of the warp mass increases and forces the supports apart.

2. A warp beam compressor comprising

means rotarily supporting the warp beam, a pair of supports mounted at opposite sides of and movable toward and from the axis of the warp beam, a compression roll rotarily mounted in each support for engagement with the warp mass on the beam, and means connecting the supports and acting, as the rolls are forced apart by the increasing diameter of the warp mass, to cause the rolls to maintain an equal, uniform and opposite pressure against the warp mass.

3. A warp beam compressor comprising means rotarily supporting the warp beam, a pair of supports mounted at opposite sides of and movable toward and from the axis of the warp beam, a compression roll rotarily mounted in each support for engagement with the warp mass on the beam, a flexible non-stretchable connector extending between the supports, and means acting, as the rolls are forced apart by the increasing diameter of the warp mass, to permit the extension of the connector and therethrough to maintain an equal, uniform and opposite pressure of the rolls against the warp mass.

4. A warp beam compressor comprising means rotarily supporting the warp beam, a pair of supports mounted at opposite sides of and movable toward and from the axis of the warp beam, a compression roll rotarily mounted in each support for engagement with the warp mass on the beam, a flexible non-stretchable connector extending between the supports, a drum about which the connector passes and to which one end is secured, and means acting, as the rolls are forced apart by the increasing diameter of the warp mass, to permit the unwinding of the drum and the consequent extension of the connector to maintain an equal, uniform and opposite pressure of the rolls against the warp mass.

5. A warp beam compressor comprising means rotarily supporting the warp beam, a pair of supports mounted at opposite sides of and movable toward and from the axis of the warp beam, a compression roll rotarily mounted in each support for engagement with the warp mass on the beam, a flexible non-stretchable connector extending between the supports, a drum about which the connector passes and to which one end is secured, and means for frictionally retarding the unwinding of the drum acting to extend the connector and to maintain an equal, uniform and opposite pressure of the rolls against the warp mass.

6. A warp beam compressor comprising means for rotarily supporting the warp beam, a pair of supports pivotally mounted beneath the warp beam at opposite sides thereof to swing toward and from the axis thereof, a compression roll rotarily mounted in each support for engagement with the

warp mass on the beam, let-off mechanism mounted on one of the supports, an idler roll journalled on the other support, a pair of guide rolls journalled beneath the warp beam, a flexible non-stretchable connector connected at one end to the one support extending therefrom beneath one guide roll around the idler roll beneath the other guide roll and to the said let-off mechanism, and means controlling the let-off mechanism acting to permit the extension of the connector and therethrough to maintain an equal, uniform and opposite pressure of the rolls against the warp mass as the rolls are forced apart by the increasing diameter of the warp mass.

7. A warp beam compressor comprising the construction defined in claim 6 in which the let-off mechanism comprises a drum 20 journalled on the support and about which the connector passes and to which the end thereof is secured, means frictionally engaging the drum, and means for adjusting the amount of friction exerted by said 25 means on the drum.

8. In a warp compressor a shaft, a plurality of drums secured to said shaft, a flexible connector for each drum passing about the drum and having one end secured there- 30 to, a friction clamp engaging the shaft, and means for adjusting the clamp to vary the amount of friction applied thereby to the shaft.

9. In a warp compressor the construction 35 defined in claim 8, together with a ratchet wheel secured to the shaft having two sets of teeth pointing in opposite directions, a pawl carrier pivoted on the shaft, and pawls pivoted on the pawl carrier to co- 40 operate with said teeth whereby the shaft may be rotated against the friction of the friction clamp in either direction.

10. In a warp compressor the construction defined in claim 8 in which each drum 45 is provided with a collar to which the end of the flexible connector is secured and in which means are provided for rotarily adjusting each collar with respect to its drum.

11. A warp beam compressor comprising 50 means for rotarily supporting the warp beam, two sets of supports mounted at opposite sides of and movable toward and from the axis of the warp beam, a compression roll rotarily mounted in the supports 55 of each set extending parallel to the axis of the warp beam and engageable with the warp mass on the beam at opposite sides thereof, and means for maintaining an equal, uniform and opposite resistance to 60 the movement of the two sets of supports away from the beam as the diameter of the warp mass increases and forces the supports apart.

12. A warp beam compressor comprising 65 the construction defined in claim 11, to-

gether with means for adjusting each roll longitudinally in its supports whereby, by adjusting the rolls in opposite directions, a warp mass on the beam of greater length than the rolls may be compressed. (6)

13. A warp beam compressor comprising the construction defined in claim 11, together with means for adjusting each roll longitudinally in its supports, and a gauge 75 mounted and longitudinally adjustable in one of the endmost supports of each set to engage the corresponding roll and maintain it in its adjusted position whereby, by adjusting the rolls in opposite directions, a warp mass on the beam of greater length 80 than the rolls may be compressed.

14. A warp beam compressor comprising the construction defined in claim 11, together with means for adjusting each roll 85 longitudinally in its supports, and a gauge mounted and longitudinally adjustable in each endmost support of each set whereby, the rolls may be adjusted in opposite directions and each roll maintained in adjusted position by one of the gauges to allow a warp mass on the beam of greater length than the rolls to be compressed. (9)

15. A warp beam compressor comprising the construction defined in claim 11, together with anti friction rolls mounted in 95 each support and forming bearings for the rolls to permit their free rotation, and an axle extending through and common to the uppermost of said anti-friction rolls in each set of supports thereby forming a guard to 100 prevent the operator being caught between the warp beam and compression rolls.

16. A warp beam compressor comprising the construction defined in claim 11, together with anti-friction rolls mounted in 105 each support and forming bearings for the rolls to permit their free rotation and an axle extending through and common to the uppermost of said anti-friction rolls in that 110 set of supports carrying the compression roll, the periphery of which in contact with the warp beam rotates downwardly, whereby a guard is presented to prevent the operator being caught between the warp beam and compressor roll. (115)

17. A warp beam compressor comprising means for rotarily supporting the warp beam, a pair of supports pivotally mounted beneath the warp beam at opposite sides 120 thereof to swing toward and from the axis thereof, a compression roll rotarily mounted in each support in parallelism with the axis of the warp beam and engageable with the warp mass on the beam at opposite sides 125 thereof, means for maintaining an equal, uniform and opposite resistance to the movement of the supports away from the beam as the diameter of the warp mass increases and forces the supports apart, and springs extending from an intermediate 130

point and connected to each support to counterbalance the weight thereof when swung away from the beam to carry its center of gravity past its pivotal point.

18. A warp beam compressor comprising means for rotarily supporting the warp beam, a pair of supports pivotally mounted beneath the warp beam at opposite sides thereof to swing toward and from the axis thereof, a compression roll rotarily mounted in each support in parallelism with the axis of the warp beam and engageable with the warp mass on the beam at opposite sides thereof, means for maintaining an equal uniform and opposite resistance to the movement of the supports away from the beam as the diameter of the warp mass increases and forces the supports apart, and latches extending from an intermediate point to engage the supports and limit their movement away from the beam when swung to carry their centers of gravity past their pivotal points.

19. A warp beam compressor comprising the construction defined in claim 17 together with latches extending from an intermediate point to engage the supports and limit their movement away from the beam.

20. A warp beamer and compressor comprising a frame, supports at opposite ends of the frame to receive and support rotarily a warp beam, beaming mechanism at one end of the frame and means for connecting it to the warp beam to effect the rotation thereof, a pair of compression rolls supported from the frame and movable parallel to and toward and from the axis of the warp beam at opposite sides thereof, means mounted on the frame for maintaining an equal uniform and opposite pressure of the rolls against the warp mass on the beam as it increases in diameter and forces apart

the rolls, and supporting rollers mounted on and beneath the frame whereby the entire unit may be moved from place to place without disturbing the relation or adjustment of the elements thereof.

21. A warp beamer and compressor comprising a frame, supports at opposite ends of the frame to receive and support rotarily a warp beam, beaming mechanism at one end of the frame and means for connecting it to the warp beam to effect the rotation thereof, means mounted on the frame for maintaining an equal, uniform opposite rolling pressure against the warp mass on the beam at opposite sides thereof as the warp mass increases in diameter, and supporting rollers mounted on and beneath the frame whereby the entire unit may be moved from place to place without disturbing the relation or adjustment of the elements thereof.

22. A warp compressor comprising a frame, a support at one end of the frame to receive and support rotarily a warp beam end, means mounted on the frame for maintaining an equal, uniform opposite rolling pressure against the warp mass on the beam at opposite sides thereof as the warp mass increases in diameter and supporting rollers mounted on and beneath the frame whereby the entire mechanism may be moved from place to place without disturbing the relation or adjustment of the elements thereof.

23. A warp beam compressor comprising means for rotarily supporting the warp beam, and means for maintaining an equal, uniform opposite rolling pressure against the warp mass on the beam at opposite sides thereof as the warp mass increases in diameter.

In testimony whereof, I have signed my name to this specification.

CHARLES P. R. THIEL.
